UNITED STATES PATENT OFFICE

111,534

DESIGN FOR A BUILDING

Harry F. Duncan, Washington, D. C., assignor to
Little Tavern Shops, Inc., Washington, D. C., a
corporation of Kentucky

Application December 13, 1937, Serial No. 73,587

Term of patent 14 years

To all whom it may concern:

Be it known that I, Harry F. Duncan, a citizen
of the United States, residing in the city of
Washington, District of Columbia, have invented
a new, original, and ornamental Design for a
Building, of which the following is a specification,
reference being had to the accompanying drawing,
forming part thereof.

The figure is a perspective view of a building
showing my new design.

The two walls of the building which are not
shown are substantially plain except for necessary
doors and windows.

I claim:

The ornamental design for a building, as shown
and described.

HARRY F. DUNCAN.
